[57] **CLAIM**

The ornamental design for a toy train track switch and track bed, as shown and described.

DESCRIPTION

FIG. 1 is a top plan of a toy train track switch and bed showing my new design;

FIG. 2 is a bottom plan view thereof;

FIG. 3 is a right side elevational view thereof;

FIG. 4 is a left side elevational view thereof;

FIG. 5 is an enlarged rear elevational view thereof;

FIG. 6 is an enlarged front elevational view thereof; and,

FIG. 7 is a top plan view of a second embodiment of a toy train track switch and track bed showing my design, the bottom plan view, left, right, front and rear elevational views thereof being mirror images of FIGS. 2-6, respectively.
